CLAIM

The ornamental design for a bended narrowing truss, as shown and described.

DESCRIPTION

FIG. 1 is a perspective view.

FIG. 2 is a side elevation view, the opposite side being a mirror image thereof.

FIG. 3 is a top plan view.

FIG. 4 is a bottom plan view; and,

FIG. 5 is an end view.

The broken line showing is for illustrative purposes only and forms no part of the claimed design.
